MEANS FOR CENTERING TUBULAR WELL STRINGS

Gerson H. Brodie, Houston, Tex.

Application September 8, 1939, Serial No. 294,010

16 Claims. (Cl. 166—1)

This invention relates to means for centering tubular well strings, such as a casing string, in a well bore.

The primary object of the invention is to insure that the cement used in the completion of the well encircles the casing completely, leaving no portion of either the wall of the bore or the casing uncovered by cement.

A further object is to furnish means that will positively move the casing away from any portion of the bore-hole wall, against which it may be leaning due to the crookness of the hole or for any other cause.

A still further object is to supply means to perform the operation of moving the casing away from the bore-hole wall in a minimum of time, without resorting to running drill pipe into the hole to accomplish the task.

Another object is to provide means sufficiently strong to be lowered into a deep hole without being damaged, and which will effect signaling the successful completion of the operation of cementing by means of the pressure gauge normally used on the mud system in drilling oil wells.

With the foregoing objects outlined and with other objects in view which will appear as the description proceeds, the invention consists in the novel features hereinafter described in detail, illustrated in the accompanying drawing, and more particularly pointed out in the appended claims.

In the drawing:

Fig. 1 is a vertical sectional view of a portion of a well hole and showing my improved means arranged therein, such means being shown partially in elevation and partially in vertical section and with a pair of centering collars with their wedges extended.

Fig. 2 is a vertical sectional view partly in elevation of one of the centering collars shown interposed in the casing string and with the wedges in retracted position.

Fig. 3 is a horizontal sectional view taken on line 3—3 of Fig. 2.

Fig. 4 is a vertical sectional view illustrating the manner in which the plug causes projection of the wedges of a centering collar.

Fig. 5 is a horizontal sectional view taken on the line 5—5 of Fig. 4.

Fig. 6 is a perspective view of one of the knurled latches employed in holding a wedge in projected position.

Fig. 7 is an elevation of one of the wedges looking from the inner side thereof.

Fig. 8 is a bottom plan view of one of the wedges.

5 Fig. 9 is a side elevation of one of the wedges.

Referring to the drawing, 10 designates the wall of a well hole in which a tubular well string, such as a casing string 11, is inserted. In the string, I interpose, at suitable points, centering collars 12; two such collars being shown in Fig. 1.

As best shown in Fig. 2, each collar may consist of a section of pipe 13 having an internal diameter substantially equal to the internal diameter of the casing sections 14, and provided at its ends with internal threads to engage external threads on the casing sections as indicated at 15.

As best illustrated in Figs. 3 and 5, the collar 12 is provided with vertically disposed slots 16 to accommodate or guide wedges or wedge-shaped centering elements 17.

The upper or small end of each wedge is hingedly connected by any suitable means located at 18 to the collar 12, and the lower or large end of each wedge is of arcuate shape as indicated at 19 so as to snugly fit the lower end portion of the slot in which the wedge operates.

As it is necessary when the wedges are projected to seal the joints between the wedges and the slots, the inner portion of each wedge is provided with oppositely disposed beveled surfaces 20 to impinge against beveled surfaces 21 at the inner portions of the slots 16. In practice the beveled section 20 of each wedge will be treated with vulcanized rubber prior to introduction of the string into the well to insure sealing when the wedges are extended. Such vulcanized rubber would be of gradually increasing thickness toward the lowermost part of the wedge flare.

At the lower end of each wedge, a knurled latch 22 (Fig. 6) extends into the slot in which the web operates, and such latch functions to hold the wedge in projected position after it has been extended, in a manner hereinafter explained. Each latch has a resilient shank 23 that is secured to the exterior of the collar 12 by means of a screw 24 or the like.

Each wedge is provided with a semi-cylindrical shield 25, secured to the wedge by any suitable means, such as screws 26, and such shields carry 55 shear pins 27 which extend into the collar 12.

(Fig. 3) and normally hold the wedges in retracted position.

The wedges are expanded by any suitable means, such as the plug 28, shown in Figs. 1, 4 and 5. Such plug is of substantially cylindrical form and has an ellipsoidal nose 29 at its lower end. Such nose is constructed of steel or any other type of hard metal and the outside diameter of the plug approaches the inside diameter of the collar.

The plug is of tubular formation and provided at its upper end with a valve seat 30 that cooperates with a rubber faced dump valve 31 having a stem 32 which extends downwardly through the plug and is normally locked in position by a shear pin 33. The valve controls ports 34 and external grooves 35, in the plug, through which the drilling mud and cement may pass at the proper time.

A sealing cup 36 is arranged at the top of the plug to insure maintenance of pressure while the plug is forced downwardly through the casing string under the pressure of the pump.

An abutment 37 attached to the stem 32 below the shear pin 33 is adapted to cooperate with the flow shoe 38 so as to cause shearing of the pin 33 and opening of the valve 31 when the plug 28 reaches the bottom of the casing string.

In operation, when it is desired to center a string of casing in the well hole, one or more of the centering collars 12 are inserted in the string at desired positions before the latter is inserted in the hole. When the string is made up, the plug 28 is dropped into the casing and allowed to float down until stopped by the retracted wedges 17 of the uppermost centering collar. A drilling mud connection is made at the top of the string and a pump pressure lower than that required to break the shear pins 27 is applied. When the pump stops, it is certain that wedges 17 are still closed. Pressure is then increased by the pump until the breaking point of the shear pins 27 is reached, at which time the pumps move freely, indicating passage of the plug through the centering collar. This procedure is repeated as the plug encounters the several collars.

When the plug forces the wedges and their appended shields 25 open, the knurled latches 22 coat with the lower ends of the wedges and prevent the return of the wedges to closed position.

When the plug 28 has been pumped to the bottom, the abutment 37 comes into forcible contact with the float shoe 38 with the result that the stem 32 is halted on its downward movement while the plug 28 shears the pin 33 and continues downwardly until it contacts such abutment. This causes opening of the valves 31 and 39 and permits the drilling mud and the cement to circulate freely through the plug, out of the casing and into the drill hole. When circulation is thus freely obtained, the casing is centered at the desired depths in the bore hole.

From the foregoing, it is believed that the construction, operation and advantages of the invention may be readily understood and I am aware that changes may be made in the details disclosed without departing from the spirit of the invention as expressed in the claims.

What I claim and desire to secure by Letters Patent is:

1. In combination, a tubular well string hav-

ing interposed therein normally retracted but projectable elements adapted to be extended outwardly from various sides of the string and to engage the wall of a bore hole for centering the string therein, a plug adapted to travel down the string and provided with means for projecting said centering elements, and latching means cooperating with said elements for holding the same in projected position.

2. In combination, a tubular well string having interposed therein normally retracted but projectable wedges, adapted to be extended outwardly from various sides of the string and to engage the wall of a bore hole for centering the string therein, each wedge having its smaller end at the top thereof, a plug adapted to travel down the string and provided with means for engaging said wedges and projecting the same outwardly as the plug travels downwardly, and latching means arranged at the lower end of each wedge for holding the same in projected position.

3. In combination, a tubular well string provided with slots at various sides thereof, normally retracted but projectable elements arranged to operate in said slots and to engage the wall of a bore hole for centering the string therein, and a plug adapted to travel down the string and provided with means for projecting said centering elements, the well string and elements having confronting beveled surfaces adapted to contact when the elements are moved outwardly to seal the joints between the elements and the slots.

4. In combination, a tubular well string having interposed therein normally retracted but projectable elements adapted to be extended outwardly from various sides of the string and to engage the wall of a bore hole for centering the string therein, a plug adapted to travel down the string and provided with means for projecting said centering elements, a shield united with each element, and fragile means for securing the shields to the well string.

5. In combination, a tubular well string having interposed therein normally retracted but projectable elements adapted to be extended outwardly from various sides of the string and to engage the wall of a bore hole for centering the string therein, a normally closed valve at the bottom of the string, and a valved plug adapted to travel down the string and provided with means for projecting said centering elements and for opening said valve.

6. In combination, a tubular well string having a normally closed valve at the lower end thereof and provided with interposed normally retracted but projectable elements adapted to be extended outwardly from various sides of the string and to engage the wall of a bore hole for centering the string therein, a tubular plug adapted to travel down the string and provided with means for projecting said centering elements, said plug having a passageway extending therethrough, a second valve adapted to close said passageway and provided with a depending stem which extends through the plug and is adapted to open the first-mentioned valve.

7. In combination, a tubular well string having a normally closed valve at the lower end thereof and provided with interposed normally retracted but projectable elements adapted to be extended outwardly from various sides of the string and to engage the wall of a bore hole for centering the string therein, a tubular plug

adapted to travel down the string and provided with means for projecting said centering elements, said plug having a passageway extending therethrough, a second valve adapted to close said passageway and provided with a depending stem which extends through the plug and is adapted to open the first-mentioned valve, and frangible means for normally holding the stem in such position as to close said second valve.

8. In combination, a tubular well string having interposed therein normally retracted but projectable elements adapted to be extended outwardly from various sides of the string and to engage the wall of a bore hole for centering the string therein, a normally closed valve associated with the well string and arranged below said elements, and valved means adapted to travel down the string, to project said centering elements and open said valve.

9. A method of centering and cementing oil well casing comprising forcing a plug down the casing and utilizing such plug to project centering elements from the casing and to open a discharge valve of the casing, and then forcing cement through said plug and valve into the bore hole in which the casing is centered.

10. A centralizing device for well casing and the like, comprising a hollow body secured to said casing, longitudinally restrained radially extensible members positioned in said body intermediate its ends, means for holding said members in a retracted position in said body to be substantially flush with its outer surface, rigid means adapted to be introduced into said body to fill the bore thereof to release said holding means and positively extend said members radially from said body, and means associated with said extensible members to retain them in an extended position independently of said rigid means.

11. A centralizing device for well casing and the like, comprising a hollow body adapted to be secured to said casing, longitudinally restrained radially extensible members movably positioned in said body, means for holding said members in a retracted position in said body, said extensible members and said holding means adapted to be actuated by means operable from the top of said casing to release said holding means and positively extend said members from said body, and means associated with said extensible members for holding them in their expanded position independently of the surface operable means.

12. A centralizing device for well casing and

the like, comprising a hollow body adapted to be secured to said casing, a plurality of longitudinal slots circumferentially spaced in said body, a longitudinally tapered foot in each of said slots, means at one end of said slots for retaining said feet against inward or outward motion therein, the wider ends of said feet adapted to be displaced outwardly from said body by a rigid object introduced therein, and means associated with said feet for holding them in their expanded position independently of said rigid object.

13. A centralizing device for well casing and the like, comprising a tubular body member adapted to be connected to a well string, longitudinal slots in said body member, a longitudinally restrained radially extensible element positioned in each of said slots, and holding means for normally holding said elements in retracted position, said holding means being releasable by a rigid object introduced into the body member to move said element outwardly from said body member.

14. A centralizing device for well casing and the like, comprising a tubular body member adapted to be connected to a well string, longitudinal slots in said body member, a longitudinally restrained radially extensible element positioned in each of said slots, holding means for normally holding said elements in retracted position, said holding means being releasable by a rigid object introduced into the body member to move said elements outwardly from said body member, and latch means cooperating with said elements for holding the same in extended position.

15. In combination, a tubular well string having interposed therein normally retracted but projectable elements adapted to extend outwardly from various sides of the string, and a valved plug adapted to travel down the string, said plug being adapted to cooperate with said projectable elements to extend the same outwardly into contact with the wall of a bore hole for centering the string therein.

16. In combination, a tubular well string having interposed therein normally retracted but projectable elements adapted to extend outwardly from various sides of the string, and a ported plug provided with an obturating member, said plug being adapted to cooperate with said projectable elements to extend the same outwardly into contact with the wall of a bore hole for centering the string therein.

CERTIFICATE OF CORRECTION.

Patent No. 2,253,415.

August 19, 1941.

GERSON H. BRODIE.

It is hereby certified that error appears in the printed specification of the above numbered patent requiring correction as follows: Page 3, second column, line 12, beginning with "13. A centralizing" strike out all to and including the word and period "member." in line 21, comprising claim 13, and for the claims now appearing as 14, 15, and 16, read 13, 14, and 15 respectively; and that the said Letters Patent should be read with this correction therein that the same may conform to the record of the case in the Patent Office.

Signed and sealed this 30th day of September, A. D. 1941.

(Seal)

Henry Van Arsdale,
Acting Commissioner of Patents.
